ATTORNEY.

UNITED STATES PATENT OFFICE.

EUGENE H. HIRNER, OF PHILADELPHIA, PENNSYLVANIA.

DESIGN FOR RELIEF BUST OF COLUMBUS.

SPECIFICATION forming part of Design No. 22,005, dated November 22, 1892.

Application filed October 28, 1892. Serial No. 450,286. Term of patent 3½ years.

To all whom it may concern:

Be it known that I, EUGENE H. HIRNER, a citizen of the United States, residing in the city and county of Philadelphia, State of Pennsylvania, have invented and produced a new and original Design for a Bust of Columbus, of which the following is a specification, reference being had to the accompanying drawings forming a part thereof.

10 The leading feature of my design for a bust of Columbus is the relief form of the same.

Figure 1 represents a view of the design. Fig. 2 represents a section thereof on a reduced scale to illustrate the relief.

In the drawings, A designates the head of Columbus, the same being nearly in profile. B designates the chest, which is three-quarters, and C designates the garments on the chest. The bust is in relief.

15 What I claim is—

20 The design for a relief bust of Columbus, as shown and described.

EUGENE H. HIRNER.
